UNITED STATES PATENT OFFICE.

ANDREW W. GRAHAM, OF BUFFALO, NEW YORK, ASSIGNOR TO THE CITY TRUST CO.,
BRANCH OF THE MARINE TRUST CO., TRUSTEE, OF BUFFALO, NEW YORK.

MATCH PACKET FOR ADVERTISING PURPOSES.

1,414,945.

Specification of Letters Patent.

Patented May 2, 1922.

Application filed January 6, 1921. Serial No. 435,443.

To all whom it may concern:

Be it known that I, ANDREW W. GRAHAM, a citizen of the United States, residing at Buffalo, in the county of Erie and State of New York, have invented certain new and useful Improvements in Match Packets for Advertising Purposes, of which the following is a specification.

This invention relates to match packets for advertising purposes and has special reference to improvements on the devices shown in my prior Patent Number 1,351,242 of August 31, 1920, and in my co-pending applications numbered respectively 429,238 and 15 429,239 and both filed December 8, 1920.

One important object of the invention is to provide improved means suitable for holding advertising matter carried by a match packet in such a way as to secure or 20 hold the match packet to a packet such as a packet of cigarettes or the like.

A second important object of the invention is to provide improved means of the above character so arranged as to expose a 25 portion of the cigarette packet for advertising purposes while at the same time having ample additional surface for displaying for advertising.

A third important object of the invention 30 is to provide a match packet with an improved collapsible wrapper so constructed and arranged that the wrapper may either be used to surround a package of cigarettes or the like or may be detached to permit direct attachment of the match packet as by adhesive means.

A still further important object of the invention is to provide a novel arrangement 35 of spring hinge for match packets of this character.

With the above and other objects in view the invention consists in general of certain novel details of construction and combinations of parts hereinafter fully described, 45 illustrated in the accompanying drawings, and specifically claimed.

In the accompanying drawings, like characters of reference indicate like parts in the several views, and:—

50 Figure 1 is a perspective view of a match packet showing one form of the attaching means.

Figure 2 is a side view of the packet illustrated in Figure 1.

55 Figure 3 is an end view thereof.

Figure 4 is a view showing a modified form of the wrapper means, this form being arranged to accommodate packages of different sizes or to be attached directly by gumming to a package. 60

Figure 5 is an end view showing the manner of attaching the forms of Figure 4 by gumming to a cigarette package.

Figure 6 is a face view of the improved form of packet having a spring hinge. 65

Figure 7 is a view thereof from the hinge edge.

Figure 8 is a section on the line VIII-VIII of Figure 6.

In the drawings illustrating the invention 70 the match packet is indicated in general at M and at P is a package of cigarettes, it being understood that this showing is typical of any small package such as tobacco, cigarettes, small cigars or anything of like 75 nature to which it may be found desirable to attach a match packet as advertising means.

In the form shown in Figures 1, 2 and 3 there is secured to the packet M a collapsible envelope having folding sides 10 and a back 11 provided with a window opening 12 so that when a package P is introduced as disclosed in Figure 1 a portion of such package will be exposed through the window 12 thus advertising the kind of cigarettes or the like which are held in the envelope while at the same time the sides and remainder of the portion 11 of such envelope afford space for the display of other advertising matter. 85

In the form shown in Figure 4 the envelope is in the shape of a wrapper strip having an approximately central portion 13 glued to or formed integrally with the bottom of the packet M. On each side of this portion M are provided folded side portions 14 normally collapsed in bellows like manner and at the free edges of the portions 14 are back portions 15 and 16 one being arranged to overlap the other. The overlapping portion is provided along its free edge with a gummed field 17. Also gummed fields 18 are provided on the rear face of the portion 13 adjacent each edge. 95

With this construction a package of cigarettes or the like may either be held to the packet by wrapping the wrapper around such cigarette package and gluing the portion 17 to the portion 15 or the side mem- 100

110

bers 14 may be torn off at their junction with the central part 13 thus exposing the gummed fields 18 which may be moistened and stuck directly on a package P as shown in Figure 5. Furthermore, if desired, the package may be secured by the gummed fields 18 and the wrapper also placed around such package. It is to be noted that with this form the device peculiarly adapts itself both to varying sizes of cigarette packages and also to different styles of packages. For instance the packet M may be made small enough to just fit a small package of cigarettes and yet by tearing off the side portions the packet may 15 be gummed on a large package of cigarettes or cigars even though the latter be too large to be embraced by the wrapper.

It is of course obvious that the exposed faces of the different forms of wrapper and 20 match packet are well adapted for the display of advertising matter.

In using this form of the device it is desirable to have a simple means for holding the match packet normally closed and to this 25 end I prefer to make this packet with a back member 18 substantially flat and a front member or top 19 in the form of a shallow tray, the two being made from a single blank of cardboard or the like and having hinged 30 connection as at 20. Centrally of the back portion 18 I provide, extending inward from the hinged edge, slits 21 and by properly compressing and hardening, as by hot stamping, the part of the back 18 between the slits 35 21 I form an outwardly projecting resilient lip 22. Moreover the top 19 is pressed as at 23 to provide a lip co-acting with the lower lip 22. From an inspection of Figure 8 it will be obvious that when the top is moved 40 around the hinge 20 the lip 23 will spring the lip 22 downward and owing to the resiliency of this lip 22 release of the top 19 will allow the lip 22 to force the part 23 upward around the hinged line and thus 45 close the packet.

There has thus been provided a simple and efficient device of the kind described and for the purpose specified.

Having thus described the invention, what is claimed as new, is:—

1. The combination with a match packet for advertising purposes; of a collapsible wrapper member secured to the back of said packet and adapted to enclose a package such as cigarettes or the like.

2. The combination with a match packet for advertising purposes; of a collapsible wrapper member secured to the back of said packet and adapted to enclose a package such as cigarettes or the like, said wrapper member being provided with a window therein wherethrough a portion of the enclosed package may be displayed.

3. The combination with a match packet for advertising purposes; of a wrapper member having a substantially central portion connected to the back of the match packet and provided on its rear side with gummed fields adjacent its edges.

4. The combination with a match packet for advertising purposes; of a wrapper member having a substantially central portion connected to the back of the match packet, said central portion being provided on its rear side with gummed fields adjacent its edges, said wrapper member further having collapsible side portions carried by the lateral edges of the central portion and having overlapping rear portions arranged for adhesive connection, said side portions and central portion being formed of paper like material whereby the side portion can be torn away from the central portion.

5. A match packet consisting of a bottom and top formed of a single blank of cardboard like material, said bottom and top being connected along a hinged line, said bottom having slits extending inward from the hinged portion and being disconnected from the top between said slits, the disconnected portion being expanded laterally and compressed to form a resilient lower lip, and an outwardly extending upper lip formed on said top and engaging said lower lip.

In testimony whereof I affix my signature.

ANDREW W. GRAHAM.
